UNITED STATES PATENT OFFICE.

HUGH G. TAYLOR, OF DENVER, COLORADO.

PUZZLE.

1,118,912.

Specification of Letters Patent. Patented Nov. 24, 1914.

Application filed February 16, 1914. Serial No. 818,863.

To all whom it may concern:

Be it known that I, HUGH G. TAYLOR, a citizen of the United States, residing at Denver, in the county of Denver and State of Colorado, have invented a new and useful Improvement in Puzzles, of which the following is a specification.

The object of this invention is to provide a simple and inexpensive puzzle in which 10 one or more hollow elements such as balls provided with apertures or openings are employed in a suitable casing having one or more transparent sides and one or more smaller elements or balls are adapted to pass 15 through said openings into the interior of said hollow elements upon sufficiently turning or shaking the casing containing them, said hollow element being provided with means for engaging the smaller element to 20 prevent it from escaping from the larger element after it has been placed therein.

The invention further provides incidental features of construction which serve to prevent the entrance of the smaller element into 25 the larger element, except in rare instances.

In the accompanying drawing forming part of this specification Figure 1 is a plan of my invention when of rectangular shape and adapted for use as a paper weight; 30 Fig. 2 is a section of Fig. 1 taken upon the line X—X; Fig. 3 is a section of the large hollow element or ball; Fig. 4 is a perspective view of the spring which is placed in the large hollow element for preventing the 35 smaller element from escaping after it has been placed therein; Fig. 5 is a plan of an alternative construction of my invention, and Fig. 6 is a section taken on the line Y—Y Fig. 5.

40 In the drawing, A indicates a suitable rectangular frame made from a single piece of metal or any other suitable material. This frame is provided with an inwardly projecting rim B around its entire inner surface, and positioned substantially midway between its outer ends. Placed against the outer ends of the frame are two opposite sides C and D made of glass or other suitable transparent material which may be secured to the frame by gluing directly thereto or by securing a strip of leather, paper or other suitable material E over the rim of the frame and the edges of said sides. The frame A and sides C and D form an enclosure within which are placed a pair of puzzle elements F and G which are adapted

to be manipulated in the puzzle frame or inclosure as will be hereinafter described. The element F is in the form of a large ball having an opening H in one side extending 60 into the ball and forming a receptacle for the element G, which is in the form of a small ball of slightly less diameter than the diameter of the opening H.

In use the frame is held in horizontal position and by tilting it the large and small balls are rolled around in the frame into position, so that the small ball may sometimes roll into the large ball, the object of the same being to cause the small ball to enter the passage H. The inward projection B acts as a guard for the large ball around the frame, which permits the small ball G to escape from the large ball, and makes it extremely difficult to cause the small ball 70 to enter the large ball. It will be noted that the distance between either side wall C or D of the frame and the guard is sufficient to allow the small ball to escape below the guard. The passage H is provided with a 80 spring catch I, which is cut from a thin strip of spring material and formed with a lateral circular inner end 2, an outwardly tapering shank 3, and a backwardly inclined spring outer end 4. This catch is inserted 85 in the passage H with its circular innermost end 2 first, the diameter of said end being substantially the same diameter as the passage so as to form a tight engagement and prevent the catch from becoming disengaged 90 from the ball. The backwardly inclined end 4 is adapted to be sprung down by the small ball G to allow it to pass into the passage H, but blocks the small ball from becoming disengaged from the passage, after it has been 95 captured. The small ball is of sufficiently small diameter to sweep over the end 4 of the catch in the passage in the large ball. In rare instances the small ball can be captured in the large ball although the task is 100 difficult to accomplish.

The frame or inclosure may be of any suitable shape, that illustrated in Figs. 1 and 2 being only one of many forms that may be employed. In Fig. 5 is illustrated a cross 105 sectional view of an alternative form showing another construction of the frame. In this view the parts J and K are made of glass or other suitable transparent material and formed with telescoping marginal sides 110 L and M, which have secured between them, an inwardly projecting guard N. After the

- frame has been assembled with the large and small elements F and G within, said parts are glued or otherwise fastened together. This construction is particularly adapted for 5 use as a paper weight, and is inexpensive. In use as many sets of balls or loosely disposed puzzle elements F and G may be employed in the inclosure produced by the frame as desired.
- 10 In accordance with the patent statutes, I have described the principles of operation of my invention together with the apparatus which I now consider to represent the best embodiment thereof but I desire to have it 15 understood that the construction shown is only illustrative and that the invention can be carried out by other means and applied to uses other than those above set forth within the scope of the following claims.
- 20 Having described my invention, what I claim as new and desire to protect by Letters Patent is:—

1. A puzzle comprising, in combination, 25 an inclosure case having a transparent side and a guard around its inner wall projecting inwardly in the inclosure, an independent freely movable element in the inclosure having an aperture in its side, a smaller independent freely movable element in said inclosure adapted to pass into the interior of 30 said hollow element and a spring catch in the aperture of said hollow element adapted to permit said smaller element to sweep past and enter said aperture but block it against

escaping from said aperture after it has been 35 captured, said guard permitting said small element escaping below it from entering the large element.

2. A puzzle, comprising, in combination, 40 an inclosure case having a transparent side, an independent freely movable element in the inclosure having an aperture in its side, a smaller independent freely movable element in said inclosure adapted to pass into the interior of said hollow element and a 45 spring catch in the aperture of said hollow element adapted to permit said smaller element to sweep past and enter said aperture, but block it against escaping from said aperture after it has been captured. 50

3. A puzzle, comprising, in combination, 55 an inclosure case having a transparent side and a guard around its inner wall projecting inwardly in the inclosure, an independent freely movable element in the inclosure having an aperture in its side, a smaller independent freely movable element in said inclosure and adapted to pass into the interior of said hollow element, said guard permitting said smaller element escaping from entering the larger element. 60

In testimony whereof, I have signed my name to this specification, in the presence of two subscribing witnesses.

HUGH G. TAYLOR.
